UNITED STATES PATENT OFFICE.

OSCAR ALSTAD, OF EVANSVILLE, MINNESOTA.

AUTOMATIC SPEED-CONTROLLED DEVICE.

Application filed April 15, 1925. Serial No. 23,321.

To all whom it may concern:

Be it known that I, OSCAR ALSTAD, a citizen of the United States, residing at Evansville, in the county of Douglas and State of Minnesota, have invented certain new and useful Improvements in Automatic Speed-Controlled Devices, of which the following is a specification.

This invention relates to an automatically operable device for controlling the speed of an automobile engine, by automatically regulating the fuel charge through the carburetor.

The device has more specific reference to an attachment which can be supplied to a conventional type of motor, such as that used upon Ford automobiles, and one feature of the invention is that it is operated from the fan shaft, an element which is in turn operated from the engine shaft.

The primary object is to generally improve upon devices of this class, by providing one of comparatively simple and durable nature, capable of being applied without requiring extensive alterations, and one that may be safely relied upon to positively operate according to the speed of rotation of the engine shaft.

Other features and advantages of the invention will become apparent during the course of the following description and drawings.

In the accompanying drawings, forming a part of this application, and in which like numerals are employed to designate like parts throughout the same:

Figure 1 is a top plan view of a part of a Ford motor, showing the improved device, in position thereon.

Figure 2 is a side elevation of the device detached.

Figure 3 is an enlarged detail perspective view of the rear end portion, showing the construction and arrangement of details more plainly.

Figure 4 is a longitudinal section through the governor slide.

Figure 5 is a detail perspective view of one of the governor arms.

Referring to the drawings in detail, the reference character 1 designates a shaft, which is connected at its forward end by a bracket arm 2, and at its rear end by a relatively long bracket arm 3. These arms diverge toward each other, and are bolted, as at 4, to the motor.

Slidable upon this shaft is the centrifugal speed governor 5 set into rotation by a pulley 6, this pulley being driven by a belt 7 trained over an additional pulley 8 on the fan shaft 9. In this connection, it will be observed that the governor is rendered very sensitive by employing two-ply arms 10 as shown in Figure 5, the outer ends of the arms of course being equipped with the usual weights. Fastened to the rear end of the shaft 1 (see Figs. 2 and 3) is a standard 11 having its upper edge twisted as at 12. Mounted upon this twisted end is an arm 13 having a downturned forward end carrying an adjusting screw 14. The opposite rear end is also downturned and disposed at the approximate angle indicated at 15 and carries a flat spring 16. Interposed between the standard 11 and the centrifugal governor 5 is what may be generally termed a slide 17, and as shown in Figure 4, this slide comprises an outer sleeve 18, an inner sleeve 19, and an intervening sleeve 20. The outer sleeve 18 is provided with a flange with which the governor is connected. The inner sleeve 19 is also provided with a flange 21, with which a yoke 22 is connected. Also connected to this flange is a rod 23, extending rearwardly through a hole in the standard 11 and bearing at its free end against the flat spring 16. Rigidly secured at its forward end to the shaft 1 is a rearwardly extending supporting member 24, upon which a bell crank 25 is pivoted, this bell crank being operated by connection 26 between the short arm thereof and the aforesaid yoke 22. An operating rod 27 is connected to the longer arm of the bell crank at one end and is connected at its opposite end to the control means 28 for a throttle valve in the carburetor 29.

In operation, it will be seen that the centrifugal governor 5 will be rotated about the shaft 1, through the medium of the pulleys 6 and 8 and the belt 7. When the speed of rotation of the governor becomes excessive, the resilient arms 10 fly out to exert an endwise thrust upon the slide 17. The slide 17 transmits this thrust through the rod 26 through the bell crank 25, thus swinging the bell crank upon its pivot and serving to push the operating rod 27 in a direction to close the throttle valve 28 of the carburetor. Obviously, by cutting off the fuel in this manner, the speed of the engine is cut down. During the aforesaid operation, the flat

spring 16 maintains a constant yielding pressure against the slide 17 through the rod 23, thus resisting the rearward sliding of the sleeve 17, serving to automatically return the 5 parts to their normal positions as the speed of the vehicle is reduced.

It is thought that persons familiar with speed controlling devices of this class will, upon carefully considering the description 10 in connection with the drawings, be able to obtain a clear understanding of the present invention. Therefore a more lengthy description need not be entered.

While the preferred embodiment of the 15 invention has been shown and described, it is to be understood that minor changes coming within the field of invention claimed may be resorted to, if desired.

I claim:

- 20 1. In a speed control device of the class described, a relatively stationary shaft, means for supporting said shaft from a motor block, a centrifugal governor slidable and rotatable upon said shaft and embodying a rotating pulley, a slide mounted upon said shaft, a bell crank supported from said shaft, a connection between said bell crank and said slide whereby the bell crank is swung upon its pivot according to the movement of the slide, and adjustable spring means supported upon said shaft and co-operable with said slide to resist said sliding movement in a rearward direction.
- 25 2. In a speed control device of the kind specified, a relatively stationary shaft, bracket arms connected to the opposite ends of said shaft and adapted to be connected to an engine motor for supporting said shaft, a

slide longitudinally movable upon said shaft, a centrifugal governor for operating said 40 slide, a standard connected with the rear end of said shaft, an arm pivotally mounted upon said standard, an adjusting screw carried by said arm and bearing against said standard, a flat spring connected to said arm and depending therefrom, and a rod carried by said slide and bearing against said spring. 45

3. In a speed control device of the class described, a relatively stationary shaft, supporting means therefor, a centrifugal governor mounted for rotation and sliding upon said shaft, a slide upon said shaft, said slide being made up of independent sections, a yoke connected with one of said sections, a bell crank, means for supporting said bell 50 crank from said shaft, a connection between said bell crank and said yoke, and spring means supported from said shaft and co-operable with said slide for resisting the sliding movement in one direction. 55

4. In a speed control device of the class described, a shaft, supporting bracket arms for said shaft, a centrifugal governor rotatable and slidable upon said shaft including a rotating pulley, a sectional slide mounted on said shaft, a standard carried by said shaft, an arm pivoted upon said standard, adjusting means for said arm, a spring carried by said arm, means interposed between said spring and slide to resist the sliding 60 movement of the slide in one direction, a bell crank, means for supporting the bell 65 crank from said shaft, and a connection between said bell crank and said slide. 70

In testimony whereof I affix my signature.
OSCAR ALSTAD.
